United States Patent Office

Des. 205,211
Patented July 12, 1966

205,211

BEVERAGE DISPENSER

Albert H. de Boer, Creve Coeur, Mo., and Robert I. Franklin, Creve Coeur, Mo. (601 S. Taylor Ave., St. Louis 10, Mo.), and Malcolm B. Sturgis, Clayton, Mo. (601 S. Taylor Ave., St. Louis 10, Mo.); said de Boer assignor to said Franklin and said Sturgis

Filed June 15, 1965, Ser. No. 85,750

Term of patent 3½ years

(Cl. D2—3)

FIG. 4.

FIG. 5.

FIG. 6.

FIG. 1 is a perspective of a beverage dispenser showing our new design;

FIG. 2 is a front view of the FIG. 1 dispenser;

FIG. 3 is an elevation of one side of our dispenser;

FIG. 4 is a plan view of our dispenser;

FIG. 5 is a view showing the bottom of our dispenser; and

FIG. 6 is a rear view of the dispenser of our invention.

The other side of the dispenser is the mirror image of the side illustrated in FIG. 3.

In FIGS. 1 and 3-5 the dispenser of our design is shown attached to a beverage container, the container being shown in broken lines for illustrative purposes only.

We claim:

The ornamental design for a beverage dispenser, substantially as shown and described.
